UNITED STATES PATENT OFFICE.

BENJAMIN GOLD, OF HOBART, INDIANA.

ART OF REPAIRING FURNACE-ROOFS.

1,316,297.

Specification of Letters Patent. Patented Sept. 16, 1919.

Application filed April 11, 1919. Serial No. 289,338.

To all whom it may concern:

Be it known that I, BENJAMIN GOLD, a subject of the King of Great Britain, residing at Hobart, in the county of Lake and 5 State of Indiana, have invented a new and useful Improvement in the Art of Repairing Furnace-Roofs, of which the following is a specification.

As a preface to the description of my invention, it may be stated that in the operation of furnaces, as, for example, open-hearth furnaces, the heat to which the roofs thereof are subjected sooner or later burns out portions of the roof structure, requiring 10 the repairing thereof. Sometimes the burned out portion extends entirely through the upper surface of the roof, and sometimes short thereof, and, in the repairing operation, the impaired portion of the roof is cut out and 15 back to a point where the roof is thickest. Centering is then placed adjacent to the opening to be filled and the repairing material, as, for example, refractory bricks, are filled into the opening upon the centering, it 20 being understood that such repairs are made as soon as possible after the furnace has ceased to be fired.

My primary object is to provide improvements in the art referred to whereby the 25 labor cost of repairing the roof will be very greatly reduced, a great saving in time and material will be effected, and, in general, a better job result, the brick-layer will be protected from the heat of the furnace, 30 which may be relatively great during the repairing operation, the repairs may be made while the furnace is very hot compared with the heat of the furnace when 35 repaired in accordance with prior methods; 40 and the spalling off of the bricks will be prevented.

Referring to the accompanying drawings, Figure 1 is a cross-sectional view of a furnace structure illustrating it in the process 45 of being repaired in accordance with my invention, the section being taken at the line 1—1 on Fig. 2 and viewed in the direction of the arrow. Fig. 2 is an enlarged section taken at the line 2—2 on Fig. 1 and viewed 50 in the direction of the arrow. Fig. 3 is a perspective view, with parts broken away, of one of the similar hanger units illustrated in Figs. 1 and 2, showing the parts in disassembled relation. Fig. 4 is a plan view 55 of the lower cross-bar of the unit, and the locking rod for holding it at one end, the

latter being shown in an intermediate position. Fig. 5 is a view like Fig. 1 showing a modification of the hanger units, the section being taken at the line 5—5 on Fig. 6 60 and viewed in the direction of the arrows; and Fig. 6, an enlarged section taken at the line 6—6 on Fig. 5 and viewed in the direction of the arrows.

Referring particularly to Figs. 1 to 4, inclusive, a furnace, the roof of which is to be repaired, is represented at 7, the roof being indicated at 8 and shown of arched form transversely of the furnace structure. The dotted line 9 represents, by way of example, 70 the inside of the roof where it is partly burned out and is to be repaired, the roof at this point, in accordance with common practice being removed to provide the rectangular-shaped opening 10 forming the 75 void to be filled, for effecting the repair. This being done, the operator positions in the opening 10, and preferably in spaced relation, hanger units which are supported from the roof at opposite sides of the opening, by resting upon the upper surface of the roof, and present a support for a plate or plates by preference of metal, which form a centering and extends to a point adjacent the underside of the roof 8. The centering 80 thus provided forms a support upon which the bricks, or other material, for filling the opening 10 are placed.

The hanger units above referred to, and in accordance with the showing in Figs. 1 90 to 4, inclusive, are each formed of a pair of side-bars 11 and 12 provided at their upper ends with outwardly-extending flanges 13 and 14, respectively, and with a lower cross-bar 15, which is pivotally connected to the 95 lower end of the bar 11, as by means of the hinge joint 16, and at its opposite end is connected indirectly with the bar 12 through the medium of a rod 17 rotatably mounted in bearings 18 and 19 secured to the bar 12, 100 the lower end of the rod 17 being provided with a cross-piece 20 which is adapted in one position of the rod 17 to be inserted through an elongated slot 21 in the cross-bar 15 as represented in Fig. 4, and upon partially rotating the rod 17 becomes interlocked with the underside of this bar, to hold the latter in the position shown in Fig. 2, the upper end of the rod 17, by preference, extending above the flange 14 of the 110 bar 12. The hinge connection 16 is shown as laterally offset from the bar 11, and

where it is thus provided the bar 11 is preferably equipped with ribs or lugs 22 spaced apart vertically on its outer face where it opposes a wall of the opening 10.

5 In the repairing of the furnace roof as stated the parts of the hanger units are assembled together as explained and then introduced into the opening 10 from the top of the roof 8 to a position in which these 10 units rest at their flanges 13 and 14 upon the portions of the roof surrounding the opening 10 as illustrated. The workman then lays across the cross-bars 15, to form the centering hereinbefore referred to, a plate or 15. plates, preferably of metal, such a plate being represented at 23 and the repairing material filled into the opening 10, as hereinbefore stated, in the particular arrangement now being described, the hanger units being 20 removable, after the repairing job has been completed. This is accomplished by the workman rotating the rods 17 to cause the cross-members 20 to register with the openings 21, as shown in Fig. 4, which permits 25 the cross-bars 15 to swing downwardly on their hinges 16, the centering 23 dropping into the furnace, the bars 11, with the cross-members 15 hanging from them then being lifted upwardly through the roof, and, like- 30 wise, the part 12, with the rods 17 thereon.

The arrangement shown in Figs. 5 and 6 constitutes a change in the hanger units only, these units represented at 24 being formed as integral structures instead of 35 separable parts, as in the construction of the preceding figures. In this arrangement, the hangers and centering would remain in the roof until burned away.

It will be noted from the foregoing that 40 the workmen in repairing the roof are stationed at all times exterior of the furnace-chamber and that the centering serves as a shield to protect the workmen against the heat of the furnace.

45 Furthermore, by repairing a furnace in accordance with my invention the repairs may be effected very expeditiously and while the furnace is relatively hot, especially because of the fact that the hanger units may 50 be quickly applied to operative position in the opening to be filled with the repair material, thereby saving the time of the workmen and minimizing the time during which the furnace is idle, with consequent saving 55 in expense of labor and operation. The centering, when of metal, also serves the useful function of permitting the fresh material filled into the opening 10 to be gradually heated, when the furnace is re-fired, with the 60 result of preventing spalling of the material, and by the time the centering has melted away, where it is permitted to remain

in the position shown in the drawings, the repairing material has become heated to such a degree that spalling will not thereafter take place. 65

Furthermore, by supporting the hanger units as by the flanges 13 and 14 resting upon the upper surface of the roof, these units are caused to take positions substantially conforming to the curvature of the upper surface of the arched roof, the centering thereby also becoming arched, as shown in Figs. 1 and 5, whereby the repairing material, when in brick form, will substantially 70 conform at its upper and lower surfaces with the arc-shaped top and bottom surfaces of the roof and thus produce a neat job. 75

What I regard as new and desire to secure by Letters Patent is— 80

1. The method of repairing furnace-roofs which consists in introducing from the top of the roof into the opening to be filled to extend across the opening and be supported on the upper surface of the roof at the opposite sides of the opening, hanger-units in a condition in which they form supports for centering, and thereupon introducing into said opening and upon said centering the material for filling said opening. 90

2. The method of repairing furnace roofs which consists in introducing from the top of the roof into the opening to be filled to extend across the opening and be supported on the upper surface of the roof at the opposite sides of the opening, hanger-units in a condition in which they form supports for centering, applying centering to the hanger-units and thereafter introducing into said opening and upon said centering the material for filling said opening. 95

3. A hanger comprising a pair of bars, a cross-bar, said bars having portions at which they are adapted to be supported at the edge of an opening in a roof, said cross-bar being 105 flexibly connected at one end with the lower end of one of the bars of said pair of bars, and means for releasably connecting said cross-bar at its opposite end with the lower end of the other bar of said pair thereof. 110

4. A hanger comprising a pair of bars, a cross-bar, said bars having portions at which they are adapted to be supported at the edges of an opening in a roof to be repaired, said cross-bar being flexibly connected at one end with the lower end of one of the bars of said pair of bars, and means for releasably connecting said cross-bar at its opposite end with the lower end of the other bar of said pair of bars, said means extending to a point adjacent the upper end of the adjacent bar for operation to release said cross-bar. 115 120
